CLOSURE FOR CONTAINERS

Thomas W. Miller, Ashland, Ohio, assignor to
The Faultless Rubber Company, Ashland, Ohio,
a corporation of Ohio

Application March 16, 1933, Serial No. 661,905

14 Claims. (Cl. 221—148)

My invention relates to closures for containers and has for an object the provision of new and improved devices of this character.

In the drawing accompanying this specification and forming a part of this application, I have shown, for purposes of illustration, one form which my invention may assume and in this drawing:

Figure 1 is an elevational view showing an illustrative embodiment of my invention as applied to a bottle,

Figure 2 is a vertical sectional view corresponding to the line 2—2 of Figure 1, while

Figure 3 is a vertical sectional view, partly in elevation, showing the parts prior to their assembly.

In the embodiment of my invention herein shown, there is provided a cap member 10, of substantially inflexible material, such as hard rubber or the like, comprising a body portion 11 having an annular seat 12 adapted to bear against the mouth of a bottle 13, and a skirt portion 14, having screw-threads 15 adapted to engage corresponding screw-threads on the neck 16 of said bottle. Extending outwardly from the seat 12 is a hollow neck portion 16 of smaller diameter than the skirt portion 14, having a tapered surface as at 17, reduced to provide a shoulder 18, and terminating in an annular flange 19, the shoulder 18 and the flange 19 defining a groove 20, providing abutments for cooperation with a flexible bulb 21.

The flexible bulb 21 is of dome-shape construction and formed of soft rubber, or the like, is adapted to engage the neck portion 16, and has a marginal edge 22 formed with a tapered section 23, facilitating application of the bulb to the neck portion 16, and engageable with the tapered surface 17 of the neck portion 16 to form a seal. The bulb 21 is further provided interiorly with a groove 24 adapted for the reception of the flange 19, the walls of the groove 24 and the flange 19 cooperating to provide interengaging abutments to hold the bulb in position upon the neck portion 16.

Mounted interiorly of the cap member 10 and neck portion 16 is a sealing member 25, formed of soft rubber, or the like, and which may be treated to render it resistant to any deterioration which ordinarily might be caused by contact with contents of the bottle 13. The sealing member 25 is provided with a flange 26 cooperable with the lip of the bottle 13 and with the seat 12 of the cap 10 to form a seal when the cap 10 is screwed home, and spaced from the flange 26

is an annular abutment 27 engaging within a groove 28 formed in the neck portion 16, and the sealing member 25 has a tapering portion 29 engaging a corresponding tapering portion 30 in the cap member 10 to form a seal. The sealing member 25 is also formed with a centrally depressed portion 31, cooperating with a beveled portion 32 of the cap 10 to form a cavity, opening through the sealing member 25, the tapered surfaces of the portions 31 and 32 facilitating drainage from the bulb 18. The sealing member 25 is further provided with a bore 33 formed with a groove 34 adapted to engage a flange 35 on one end of a dropper tube 36, and the dropper tube 36 is held firmly in position through provision of a bead 37 formed at the end of the bore 33.

The construction herein described is very simple and economically manufactured, and provides a bottle closure readily disassembled for cleansing purposes though normally firmly held in assembled position, and the bulb 21 and the sealing member 25 may be removed from the cap member 10 independently of one another, and thus one may be removed without disturbing the other. It will be appreciated that the construction described provides an air-tight and leak-proof bottle closure by reason of provision of the cooperating tapering surfaces 17 and 23 of the cap 10 and bulb 21, and the cooperating tapering surfaces 29 and 30 of the sealing member 25 and cap 10, and when the cap 10 is screwed onto the neck of the bottle 13, the flange 26 of the sealing member 25 is tightly clamped between the mouth of the bottle 13 and the annular seat 12 of the cap 10.

It will be obvious to those skilled in the art, that the embodiments of my invention herein shown and described may be variously changed, used, or modified, all without departing from the spirit of my invention or sacrificing the advantages thereof, and it therefore will be understood that the disclosure herein is illustrative only, that my invention embodies advantages and uses other than those particularly pointed out or suggested herein, and that my invention is not limited thereto.

I claim:

1. A combined bottle closure and liquid dropper, comprising: a cap member adapted to engage the neck of a bottle, sealing means carrying a dropper tube, and cooperable with said cap and said bottle neck to effect sealing engagement therebetween, and a dome-shaped

- yieldable bulb carried by said cap member and communicating with said dropper tube.
2. A combined bottle closure and liquid dropper, comprising: a cap member adapted to engage the neck of a bottle and having a projecting neck portion provided with an abutment extending about the same, sealing means disposed within said cap member, carrying a dropper tube, and cooperable with said cap and said bottle neck to effect sealing engagement therebetween and a yieldable bulb communicating with said dropper tube and having an abutment interengaging with the abutment on the projecting neck portion of said cap member.
3. A combined bottle closure and liquid dropper, comprising: a cap member adapted to engage the neck of a bottle and having a projecting portion provided with an abutment extending about the same and an adjacent tapered section; sealing means disposed within said cap member, carrying a dropper tube, and cooperable with said cap and said bottle neck to effect sealing engagement therebetween, and a yieldable bulb communicating with said dropper tube and having an abutment interengaging with the abutment on the projecting neck portion of said cap member, and a tapered section facilitating application of said bulb to said neck portion, and engageable with the tapered section of said projecting neck portion.
4. A combined bottle closure and liquid dropper, comprising: a cap member adapted to engage the neck of a bottle and having a projecting portion provided with an abutment extending about the same and an adjacent tapered section; sealing means disposed within said cap member and composed of soft rubber treated to render the same resistant to any deleterious action by contact with contents of said bottle, said sealing means carrying a dropper tube, and cooperable with said cap and said bottle neck to effect sealing engagement therebetween, and a bulb of soft rubber communicating with said dropper tube and having an abutment interengaging with the abutment on the projecting neck portion of said cap member, and a tapered section facilitating application of said bulb to said neck portion, and engageable with the tapered section of said projecting neck portion.
5. A combined bottle closure and liquid dropper, comprising: a cap member adapted to engage the neck of a bottle, sealing means carrying a dropper tube and cooperable with said cap and said bottle neck to effect sealing engagement therebetween, and a yieldable bulb communicating with said dropper tube, said cap member communicating with the interior of said bulb and having a cavity the walls of which are depressed toward the center to facilitate draining of said bulb.
6. A combined bottle closure and liquid dropper, comprising: a hard rubber cap adapted to fit a bottle neck, having a bulb of soft rubber extending externally thereof and connected to the exterior portion of said cap, and a sealing member of soft rubber disposed within said cap and connected to the interior thereof and carrying a dropper tube, said sealing member and said cap being apertured to afford communication between said bulb and said dropper tube.
7. A combined bottle closure and liquid dropper, comprising: a cap member adapted to engage the neck of a bottle and having a projecting portion provided with an abutment extending about the exterior thereof, and an abutment
- extending about the interior thereof; sealing means disposed within said cap member and having an abutment cooperable with the interior abutment of said cap, said sealing means being operable to effect sealing engagement between said cap and said bottle neck, and carrying a dropper tube adapted to project into the bottle neck, and a yieldable bulb communicating with said dropper tube and having an abutment interengaging with the exterior abutment on the projecting neck portion of said cap member.
8. A combined bottle closure and liquid dropper, comprising: a cap member adapted to engage the neck of a bottle and having a projecting portion provided with an abutment extending about the exterior thereof, and an abutment extending about the interior thereof; sealing means disposed within said cap member and having an abutment cooperable with the interior abutment of said cap, said sealing means being operable to effect sealing engagement between said cap and said bottle neck, and carrying a dropper tube adapted to project into the bottle neck, and a yieldable bulb communicating with said dropper tube and having an abutment interengaging with the exterior abutment on the projecting neck portion of said cap member, said cap member and said sealing means communicating with the interior of said bulb and each having an aperture the walls of which are depressed toward the center, said apertures cooperating to form a cavity to facilitate draining of said bulb.
9. A combined bottle closure and liquid dropper, comprising: a cap member adapted to engage the neck of a bottle and having a projecting portion provided with an abutment and an adjacent tapered section extending about the exterior thereof, and an abutment and a tapered portion extending about the interior thereof; sealing means disposed within said cap member, composed of soft rubber treated to render the same resistant to any deleterious action by contact with contents of said bottle, and having an abutment and a tapered portion cooperable with the interior abutment and tapered portion of said cap, said sealing means being operable to effect sealing engagement between said cap and said bottle neck, and carrying a dropper tube adapted to project into the bottle neck, and a dome-shaped soft rubber bulb communicating with said dropper tube and having an abutment interengaging with the exterior abutment on the projecting neck portion of said cap member, and a tapered section facilitating application of said bulb to said neck portion, and engageable with the tapered section of said projecting neck portion.
10. A combined bottle closure and liquid dropper, comprising; sealing means; a dropper tube carried by said sealing means; a cap, adapted to be secured to the neck of a bottle in position clamping said sealing means between said cap and said bottle neck; and a bulb, independent of said sealing means, carried by said cap, and communicating with said dropper tube to in-draw fluid into said tube and discharge such fluid from said tube.
11. A combined bottle closure and liquid dropper, comprising; sealing means, composed of rubber resistant to deleterious action by contact with the contents of said bottle; a dropper tube carried by said sealing means; a cap, adapted to be secured to the neck of a bottle in position clamping said sealing means between said cap

- and said bottle neck; and a bulb, composed of flexible rubber, independent of said sealing means, carried by said cap, and communicating with said dropper tube to indraw fluid into said tube and discharge such fluid from said tube. 5
12. A combined bottle closure and liquid dropper, comprising: sealing means; a dropper tube carried by said sealing means; a cap, adapted to be secured to the neck of a bottle in position 10 clamping said sealing means between said cap and said bottle neck; a bulb, independent of said sealing means, and communicating with said dropper tube to indraw fluid into said tube and discharge such fluid from said tube; and cooperating abutments on said bulb and on said cap, whereby said bulb is detachably carried by said cap. 15
13. A combined bottle closure and liquid dropper, comprising: a cap, adapted to be secured to the neck of a bottle; sealing means, disposed within said cap and cooperable with said cap and said bottle neck to effect sealing engagement therebetween when said cap is assembled on said neck; a dropper tube, carried by said sealing means; and a bulb, independent of said sealing means, communicating with said dropper tube to indraw fluid into said tube and discharge such fluid from said tube, and provided with an inwardly-directed abutment interengaging said cap abutment, whereby said bulb is carried by said cap detachably, having its open end embracing a portion of said cap. 20
